UNITED STATES PATENT OFFICE.

OSVIL T. EDWARDS, OF JACKSONVILLE, FLORIDA.

WAY-BILL INDEX.

1,176,043.

Specification of Letters Patent. Patented Mar. 21, 1916.

Application filed April 4, 1913. Serial No. 758,983.

To all whom it may concern:

Be it known that I, OSVIL T. EDWARDS, a citizen of the United States, residing at Jacksonville, in the county of Duval and State of Florida, have invented a new and useful Way-Bill Index, of which the following is a specification.

The present invention relates to improvements in way-bill index sheets, the primary object of the invention being the provision of a sheet whereby way bills taken into account or reported, or transferred are properly indexed according to their date and in certain columns according to the last digit 15 of the way-bill serial and number, thus producing a sheet or book of sheets whereby the bills are readily posted in a systematic manner regardless of when received, the date of the bill indicating the page upon which the 20 same is written while the last digit of the way-bill serial and number will indicate the column in which the same is posted.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

In the drawings—Figure 1 represents a single sheet or page, the same being cut 35 away centrally and foreshortened, with examples written thereupon showing the system as in operation. Fig. 2 is a plan view of a way bill. Fig. 3 is a similar view of the freight bill filled out according to the way 40 bill as indicated in Fig. 2. Fig. 4 is another way bill showing the method of writing thereupon the transfer and other data necessary.

Referring to the drawings, and more particularly to Figs. 1, 2 and 3, the index sheet or page 1 as shown in Fig. 1 is provided with, one, or a portion of one page, for each day in the month, according to the volume of business and thus the date 2 of the way 50 bill will at once indicate that the same is to be placed upon the coincident numbered page, as in this instance, February 8, 1913, there being one page or a portion of a page for each day in the year, so that the date of 55 the way bill 3 as illustrated in Fig. 2 will be taken for the main indication to be em-

ployed in posting the way bill in the index. Thus the way bill 3, as shown in Fig. 2 is dated February 8, 1913, will be posted on the February 8, 1913, page of the index 60 sheet 1, said index being divided vertically into columns 4 from 0 to 9 there being two columns 4' at the extreme right to be used for overflow indexes or when the spaces in the other vertical columns have been completely filled, this, however, may be dispensed with according to the volume of business done at a station. Each of the respective columns 4 or 4' under the respective numbers or ciphers, are divided into three 70 main indices 5, 6 and 7, as indicated at the top of the respective columns "Way bill from", "Way bill", and "Pro. or tran. car". The column 5 under "Way bill from" is for the reception of the name of the station of 75 origin, which in the instance of the bill shown in Fig. 2, is Richmond, Virginia, thus "Richmond" is posted in the column 1 as in Fig. 1. At the top of each one of the vertical columns 8 and 9 under the "Way bill", 80 column 6 is posted the abbreviations "Pref." and "No." and in column 9, throughout the full length thereof, is the cipher, indicated at 10, which corresponds with the main cipher of the column 4 or 4', the first column containing "0" so that as the way bill indicated in Fig. 2 is serial and number K 12470, the prefix or serial K is placed in the column 8 below "Pref." while the zero or 85 last digit of the number indicates that such number should be placed in the zero column 9 and therefore in the position, as shown in Fig. 1. Thus it will be seen that the way bill, as indicated in Fig. 2, is positioned upon the page or index for February 8, 90 1913, in the zero column 4 and all that is necessary in locating the position of the way bill is to ascertain the last digit of its number and its date of origin. The way bill is 95 posted according to its origin date and regardless of the date received, thus placing in the index, the way bill not as received but according to the date of issue. Where the way bill 3 is taken into account or re-billed, the revising or expense bill clerk as 100 indicated in Fig. 2, "Florida transfer, Florida" writes in red ink, as at 12, upon the face of the way bill in the second column 11 or the column of the "consignee", the abbreviation "Pro." and the number, which 105 in this instance is H 8798 and the date of receipt as February 10, 1913, the same either 110

being written or indicated by numerals, preferably numerals, as indicated in Fig. 2 and posted in the "Pro. or transfer car" column, as indicated in the 0 column of Fig. 1. Thus it will indicate upon the index that the freight from "Richmond" according to the way bill as 3 was rebilled at the "Florida transfer, Florida", on "Pro." H 8798 on February 10, 1913, the index indicating at a glance the serial number of the way bill and the number of the "Pro." on which the way bill was rebilled on February 10, 1913.

In Fig. 3 is indicated the freight bill 13, 15 which is readily made out from the way bill 3, the same indicating at a glance that the "Pro. No." is H 8798 and that the way bill number is K 12470 dated February 8, 1913 originated in car 33,768 from Richmond, 20 Virginia, thus indicating upon the face of the freight bill the addresses of the consignor and the consignee and as to whether the freight was transferred or came through in the same car from the point of origin.

In Fig. 4, the collect way bill 14 is numbered K 471, and as its date is February 8, 1913, the same is posted in the second column 4 of the index sheet 1 as shown in Fig. 1. As this freight is billed through to Tampa, Florida, from Richmond, Virginia, the transfer clerk at Florida Transfer, Florida, stamps in the second column 15 as indicated, the indication that the freight was transferred from the car "ACL 33769 to car No. ACL 39670" under date of February 10, 1913, the transfer clerk initialing the same as indicated at "J. W. J.". Thus a book composed of three hundred and sixty-five pages 1, may be used as a record 40 of freight transferred and not taken into account by showing under "Station pro. No." first, the short or loading number of car from which the freight is unloaded, and secondly, the short or loading number into 45 which the freight is transferred. All modern transfer stations list all cars unloaded and loaded according to the position or board number, as well as the number of the car, therefore with the index of these short numbers, reference can be made to the record, showing both short number and actual car numbers, seal record and the break bulk points of cars loaded and unloaded. Regardless of the nature of transfer records 50 kept, it is necessary to always refer to the seal and loading record in handling papers, hence this index book will be found a great time saver, both in posting transfer records

and in handling tracers, etc. On the face of the way bill 14, in column 16, is stamped 60 the exception number such exception number being recorded upon the index sheet above the car number and date, as indicated at 17 in Fig. 1, as "T 1688", thus corresponding with the number in connection 65 with the stamp number upon the way bill 14 in column 15, as illustrated in Fig. 4.

In using the present device as a way bill index, a page or more or a portion thereof according to the volume of business, for 70 each day in the month, is employed, the same including the space at first of each month, for way-bills received bearing no date. The way bills are thus entered as before described, regardless of when received on 75 pages corresponding with the dates of such bills, those being posted in the respective columns 4 from 0 to 9, according to the closing digit in the way bill number, and if no way bill number is given, it is preferred that such way bill be posted in the "0" column 4 as "No number", the words "No number" being written in columns 8 and 9 under "Pref. No." In practice, the expense bill clerk should enter "Pro. No." on the face 80 of the way bill and such way bill should be placed in date order before indexing, it having been discovered with this index that 85 way bills can be posted per hour and such posting of the way bills will place them in 90 the date order for reporting.

What is claimed is:

In a means for posting way bills, a record book and a way bill, the book comprising 95 pages each provided with a column of single, identical digits, and the way bill having a number, the last digit of which corresponds to the digits in the column, all of the other digits in the number of the way bill constituting indicia peculiar to the way 100 bill and independent of any marking on the page of the book, the way bill having a date, and the pages of the book being dated, thereby to locate the entry page of the bill independently of the number of the bill, to 105 simplify the number of the bill and to reduce that portion of the number on the bill which relates to the book as distinguished from the bill itself.

In testimony that I claim the foregoing 110 as my own, I have hereto affixed my signature in the presence of two witnesses.

OSVIL T. EDWARDS.
